CURRENT-COLLECTING DEVICE.

1,244,476.

Specification of Letters Patent.

Patented Oct. 30, 1917.

Application filed July 3, 1914. Serial No. 848,848.

To all whom it may concern:

Be it known that I, JOHN S. DEAN, a citizen of the United States, and a resident of Wilkinsburg, in the county of Allegheny 5 and State of Pennsylvania, have invented a new and useful Improvement in Current-Collecting Devices, of which the following is a specification.

My invention relates to dynamo-electric 10 machines, and it has special reference to the construction and operation of current-collecting devices for use in such machines.

The object of my invention is to provide 15 a device of the above-indicated character which shall be relatively simple and inexpensive in construction and reliable in operation.

More specifically stated, the object of my 20 invention is to provide a relatively short and advantageously located conducting member or shunt for conducting current around the spiral spring which is customarily provided in many types of current-collecting devices; a simple and compact 25 means for substantially eliminating lateral restraint from the coils of the spring; and a novel pawl, whereby the operative positions of the coöperating ratchet member are greatly increased over the number of 30 ratchet teeth.

Heretofore, in certain types of current-collecting devices of the class indicated, the shunt referred to has extended from a point 35 near the brush, or other current-collecting member, in a complete loop around the coiled spring, thus being of relatively great length and quite liable to be injured. Also, the yoke member, which partially incloses the spiral spring, has been provided with 40 substantially flat internal faces, thereby causing a lateral restraint of the coils of the spring, with consequent sluggishness of action. Moreover, the coöperating pawl and ratchet members have been of the ordinary 45 type, wherein the number of operative positions of the ratchet is equal to the number of teeth thereof.

According to my present invention, I provide a suitably connected shunt which is disposed wholly on the same side of the spring as the brush, or other current-collecting member, and is thus relatively short and free from obstructions and, consequently, is not liable to damage and is capable of 55 readily radiating the heat caused by the

conduction of current. By providing centrally-located internally turned bearing edges or flanges on the yoke member, only the innermost coils of the spring are engaged, thereby allowing a movement of the 60 majority of the coils which is perfectly free from lateral restraint. I provide also a pawl member having a tooth-engaging tip and one or more edge notches which are adapted to be engaged by the teeth of the co- 65 operating ratchet, under predetermined conditions, and thus permit of a number of uniform rotative steps which is a multiple of the number of ratchet teeth, thereby allowing a predetermined relatively fine adjustment 70 of the force exerted by the spring upon the brush. Moreover, it will thus be seen that, with a relatively small increase in the cost of manufacture, the same ratchet may be readily adapted for use in different structures, changes being made only in the pawl 75 member.

In the accompanying drawing, Figure 1 is a view, partially in side elevation and partially in section, of a current-collecting device constructed in accordance with my invention; Fig. 2 is an enlarged view, in elevation, of a portion of the device illustrated in Fig. 1; Fig. 3 is a sectional view taken on the line III—III of Fig. 2; and Fig. 4 85 is a modified form of a portion of the apparatus shown in Fig. 2.

Referring to Fig. 1 of the drawing, the construction here shown comprises a suitable supporting member 1, such as the frame 90 of a dynamo-electric machine which is provided with a commutating cylinder 2 or other current delivering surface; a current-collecting device 3, a plurality of suitable clamping members 4; and a stud bolt and 95 coöperating nut 5 for securing the current-collecting device 3 to the supporting frame 1.

The device 3 comprises a current-collecting member such as a brush 6 of ordinary construction which is adapted to slide within an aperture 7 at one end of the holding frame of the device; a spring-containing compartment 8 which is disposed adjacent to the brush 6; spring means 9 for biasing the brush 6 to engage the commutator cylinder 2; a substantially closed side 10 for the compartment 8 which is disposed adjacent to the surface 2; suitable clamping means 11 for securing the spring means 9 to the frame; an aperture 12 adapted to re- 110

ceive a suitable conductor (not shown) which may be readily held in position by means of a bolt 13 or other suitable means; one or more standards or rods 14 which are 5 suitably insulated from the current-carrying parts of the device and which extend between the clamping members 4; one or more insulating members 15 that are severally associated with the standards 14 and 10 have a corrugated surface for a well known purpose; and a conducting member or shunt 16 which is connected in parallel circuit relation to the spring means 9 for preventing the flow of an injurious amount of current 15 through the spring means.

The means 9 comprises a plurality of convolutions 17 of a suitable resilient material, the innermost end 17^a of which is suitably secured within a slot 18 in a centrally located sleeve member 19, to one end of which is attached a ratchet member 20 having a predetermined number of teeth 20^a, which are spaced apart by a pitch distance "P." A rod 21 centrally extends through the 25 sleeve 19 and is suitably secured in the frame of the current-collecting device. A yoke member 22 partially incloses the spring means 9 and is provided with centrally-located inwardly turned flanges 23, for bearing 30 upon the sleeve member 19 and for engaging the innermost coils of the spring. A pawl member 24 is adapted to coöperate with the ratchet member 20, and is pivotally mounted upon a pin member 25 which is 35 secured to the yoke member 22. A projecting arm or finger 26 is suitably secured to the yoke member 22 for biasing the brush 6 to engage the surface 2, and a suitable shield member 27 for the finger 26 is provided. 40

The shunt 16 extends from the outer end of the finger 26, intermediate the spring and the pin member 25 to the closed side 10, of the compartment 8, to which it may be 45 secured, near the brush 6, by means of a rivet 28 or other suitable means. The shunt 16 is thus wholly disposed on the same side of the spring as the brush 6 and, consequently, is of relatively short length and 50 free from obstruction.

The pawl member 24 is provided with a suitable tooth-engaging tip 29 and one or more edge notches 30, as shown in Figs. 2 and 4, respectively. Preferably, the notches 55 30 are disposed at such a distance from the tooth-engaging tip 29 or from the preceding notch, with respect to the pitch distance "P" of the ratchet teeth, that uniform rotative steps of the ratchet are made upon the engagement of the ratchet teeth by the tip 29 and the notches 30, in succession. The number of operative positions of the ratchet member is thus a multiple of the 60 number of ratchet teeth, and any desired rate of adjustment of the spring means 9

may be readily effected by the variation of the number of notches in the pawl. For example, the pawl illustrated in Fig. 2 is adapted to permit twice as many operative positions of the ratchet member as there are 65 ratchet teeth. Broadly stated, if the pawl has n edge notches, the number of operative positions of the ratchet member equals $(n+1)$ times the number of ratchet teeth. I desire it to be understood that although 70 in the specification and claims I have employed the terms "current-collecting member" and "current-delivering surface," I do not wish these terms to be construed as limiting the invention to use in a generator, 75 inasmuch as it will be readily apparent that the invention is equally applicable to electric motors, which have a "current-delivering member" and a "current-collecting surface." 80

I do not wish to be restricted to the specific structural details and arrangement of parts herein set forth, but desire that only such limitations shall be imposed as are indicated in the appended claims. 85

I claim as my invention:

1. In a brush-holder, the combination with a brush, a holding frame having a guiding aperture for said brush at one end, and an adjacent compartment provided with a substantially closed side, and a spiral spring operatively disposed in said compartment and having its outer end secured to said frame near said closed side; of a yoke member actuated by said spring and inclosing 95 a portion of the periphery thereof, a pin extending through the sides of said yoke member, a pawl pivotally mounted on said pin, a coöperating ratchet secured to the inner end of the spring, a finger attached to 100 said yoke for biasing the brush in a predetermined direction, and a flexible member of relatively large current-conducting capacity connected between said finger and said closed side near the brush and disposed 110 intermediate the spring and said pin and wholly on the same side of the spring as the brush.

2. In a brush-holder, the combination with a brush, a holding frame therefor, and a spiral spring supported by said holding member, of a yoke member projecting beyond a portion of the periphery of the spring member and actuated thereby to bias the brush in a predetermined direction and having 115 portions thereof projecting inwardly for engaging a relatively small portion of the spring member, whereby the greatest portion of the spring member is entirely free 120 from lateral restraint. 125

3. In a brush-holder, the combination with a brush, a holding frame therefor, a rod transversely supported in said frame, and a spiral spring encircling said rod and supported by said frame, of a yoke member 130

- partially inclosing said spring and actuated thereby to bias the brush in a predetermined direction and embodying centrally located internal flanges for engaging only the inner-
5 most coils of the spring, whereby the greater portion of the coils is entirely free from lateral restraint.
4. In a brush holder, the combination with a brush, a holding frame therefor, a rod transversely supported in said frame, a sleeve loosely surrounding said rod, and a spiral spring encircling said sleeve and having its inner end secured to said sleeve and its outer end secured to said frame, of a yoke member partially inclosing said spring and actuated thereby, a finger secured to said yoke member for biasing said brush in a predetermined direction, and means for varying the force exerted by said spring, 10 said yoke member being provided with inwardly turned bearing edges on said sleeve, whereby only the innermost coils of the spring come in contact with the internal faces of the arms of said yoke member.
5. In a current-collecting device, the combination with a current-collecting member, a holding member therefor, and a spiral spring operatively disposed in said holding member for biasing said current-collecting member in a predetermined direction, of means for varying the force exerted by said spring comprising a toothed member operatively secured thereto and a cooperating pawl member embodying means for permitting more operative positions of said toothed member than the number of teeth thereof.
6. In a current-collecting device, the combination with a current-collecting member, a holding frame therefor, and a spiral spring operatively disposed in said frame for biasing said current-collecting member in a predetermined direction, of means for varying the force exerted by said spring comprising a ratchet member operatively secured thereto and having a predetermined number of teeth, and a cooperating pawl member embodying means for permitting a number of operative positions of said ratchet member which is a multiple of said number of teeth.
7. In a brush-holder, the combination with a brush, a holding frame therefor, a spiral spring operatively disposed in said frame, and means actuated by said spring for biasing said brush in a predetermined direction, of means for varying the rotative force exerted by said spring comprising a ratchet member operatively secured thereto and having a predetermined number of teeth, and a cooperating pawl carried by said means and having a tooth-engaging tip and one or more edge notches adapted to be engaged by the teeth under predetermined conditions.
8. In a brush-holder, the combination with a brush, a holding frame having a guiding aperture for said brush at one end and an adjacent compartment, a spiral spring operatively disposed in said compartment and having its outer end secured to said frame, and a yoke member actuated by said spring and bridging a portion of the periphery thereof and adapted to bias said brush in a predetermined direction, of means for varying the rotative force exerted by said spring in relatively small steps comprising a ratchet member operatively secured to the inner end of said spring and having a predetermined number of teeth, and a cooperating pawl having a tooth-engaging tip and one or more edge notches for receiving said teeth under predetermined conditions and spaced at intervals adapted to permit uniform rotative steps of said ratchet member.
9. A current-collecting device comprising a current-collecting member, a holding member therefor, and a spiral spring member operatively disposed in said holding member, of conducting means connected in parallel circuit relation to said spring member and disposed intermediate the spring member and the current-collecting member, means actuated by said spring member for biasing said current-collecting member in a predetermined direction and embodying means associated with the spring member for preventing lateral restraint of the coils thereof, and means for varying the force exerted by said spring member comprising a toothed member operatively secured thereto, and a cooperating pawl member embodying means for permitting more operative positions of said toothed member than the number of teeth thereof.
10. A current-collecting device comprising a current-collecting member, a holding frame therefor, and a spiral spring member operatively disposed in said holding member, of a yoke member actuated by said spring member for biasing the current-collecting member in a predetermined direction and embodying means projecting internally from the sides of said yoke member for engaging a relatively small portion of the spring member, whereby the greater portion of the spring member is entirely free from lateral restraint, conducting means connected between said yoke member and said frame and wholly disposed on the same side of the spring member as the current-collecting member, and means for varying the force exerted by said spring member comprising a ratchet member operatively secured thereto and having a predetermined number of teeth, and a cooperating pawl member embodying means for permitting a number of operative positions of said ratchet member which is a multiple of said number of teeth.
11. A brush-holder comprising a brush, a holding frame having a guiding aperture for said brush and a compartment having a substantially closed side, a rod transversely

- supported in said frame, a spiral spring operatively disposed in said compartment to encircle said rod and having one end secured to said frame near said closed side, a yoke member projecting beyond a portion of the periphery of the spring member and actuated thereby to bias the brush in a predetermined direction and embodying centrally located internal flanges for engaging only the innermost coils of the spring, a conducting member connected between said yoke member and said closed side and disposed near said spring on the same side thereof as said brush, and means for varying the rotative force exerted by said spring comprising a ratchet member operatively secured thereto and having a predetermined number of teeth, and a coöperating pawl carried by said yoke member and having a tooth-engaging tip and one or more edge notches adapted to be engaged by the teeth under predetermined conditions.
12. A brush-holder comprising a brush, a holding frame having a guiding aperture for said brush at one end and an adjacent compartment having a substantially closed side, a rod transversely supported in said frame, a sleeve loosely surrounding said rod, a spiral spring operatively disposed in said compartment to have its inner end secured to said sleeve and its outer end secured to said frame near said closed side, a yoke member actuated by said spring and bridging a portion of the periphery thereof and having inwardly turned bearing edges on 35 said sleeve, whereby only the innermost coils of the spring came in contact with the internal faces of the arms of said yoke member, a pin extending through the sides of said yoke member, a finger secured to said yoke member for biasing said brush in a predetermined direction, a flexible member of relatively large current capacity connected between said finger and said closed side near the brush and disposed intermediate 40 the spring and said pin and wholly on the same side of the spring as the brush, and means for varying the rotative force exerted by said spring in relatively small steps comprising a ratchet member secured to said 45 sleeve and having a predetermined number of teeth, and a coöperating pawl pivotally mounted on said pin and having a tooth-engaging tip and one or more edge notches for receiving said teeth under predetermined 50 conditions and spaced at intervals adapted to permit uniform rotative steps of said ratchet member.
- In testimony whereof, I have hereunto subscribed my name this 26th day of June, 55 1914.
- JOHN S. DEAN.
